CLAIM

The ornamental design for an aspirator head, as shown and described.

DESCRIPTION

FIG. 1 is a top, perspective view of an aspirator head showing my new design;

FIG. 2 is a top plan view thereof, the bottom plan view being an identical mirror image;

FIG. 3 is a front elevational view thereof, the rear elevational view being an identical mirror image;

FIG. 4 is a right side elevational view thereof;

FIG. 5 is left side elevational view thereof;

FIG. 6 is a sectional view taken along the line 6-6 of FIG. 2; and,

FIG. 7 is a sectional view taken along the line 7-7 of FIG. 2. The dash-dot-dash broken lines represent the boundaries of the claimed design and form no part thereof. The dash-dot broken lines illustrate the portions of the aspirator head which form no part of the claimed design.
